JEAN B. DAUDELIN AND EUSEBE H. DAUDELIN, OF FALL RIVER, MASSACHUSETTS.

SHUTTLE.

1,182,148.

Specification of Letters Patent.

Patented May 9, 1916.

Application filed October 24, 1914. Serial No. 868,523.

To all whom it may concern:

Be it known that we, JEAN B. DAUDELIN and EUSEBE H. DAUDELIN, citizens of the United States, residing at Fall River, county of Bristol, Commonwealth of Massachusetts, have invented certain new and useful Improvements in Shuttles, of which the following is a specification.

This invention relates to hand threading shuttles and particularly to a guard for preventing dethreading of the shuttle during its run.

Our present invention is a development and an improvement over the shuttle shown in a prior application filed by us May 12, 1913, serially numbered 766,962 to which reference is made as illustrating the specific type involved herein.

This invention, while having in view the same general object as our prior application had, namely to prevent the dethreading tendency of the shuttle due to the writhing and twisting of the thread during the run of the shuttle, by means of a special form 25 of wire guard which obviated the use of the customary expensive metal bushing, has for its further object to provide a one piece construction combining in its nature the functions of a guard and a thread tensioning 30 device.

The present invention is characterized by the fact that the guard and tensioning device is made of a single length of wire which is given a form designed to both prevent 35 escape of the thread by "ballooning" and like dethreading actions during the run of the shuttle and to exert a uniform tension during the run of the thread. Our guard therefore does away with the usual guard 40 and wear post which served as a tensioning device and past which the thread was drawn.

The construction and operation of our device will be more fully disclosed in the 45 specification which follows and in the drawings forming a part of that specification we have shown as an illustrative embodiment a form of guard which not only clearly illustrates the principles involved but is in itself 50 a form proven to be satisfactory in practice and well adapted to the requirements of manufacture.

Throughout specification and drawings like reference numerals are correspondingly 55 applied and in the drawings:

Figure 1 is a plan view of the threading

end of a shuttle equipped with our invention, Fig. 2 is a longitudinal view, partly in section, of the same. Fig. 3 is a view of the thread guard removed from the shuttle. 60 Fig. 4 is a side elevation of the threading end of the shuttle and, Fig. 5 is a vertical section on the line 5—5 of Figs. 1 and 2.

The shuttle body 1 may be of any construction having a bobbin chamber 2 in which is located a bobbin 3 on which is wound a thread T. From the forward end 65 of the bobbin chamber 2 leads the eye 4 to which the threading slots 5 and 6 connect. The slot 5 in the form shown is diagonally 70 disposed with respect to the longitudinal axis of the shuttle and so sawed as to develop a curve on the shuttle top. The slot 6 connects the slot 5 with the eye 4 and preferably enters said eye at a point near 75 its top.

In order to facilitate entry of the thread T into the slot 5 we provide a guide shaped to overlie the slot 5 and so formed as to guide the thread in such a way that 80 although the thread is originally applied to the outside of the guide it will transfer itself to the inside of the guide in the course of the usual motions of drawing it through the slot into the eye. This guide comprises a 85 reversely curved top bar 7 held in place across the slot 5 by a forward downwardly bent end 8 and a rear downwardly bent end 9, which ends are driven into the wood of the shuttle to hold the guide in proper relation to the slot 5. The forward curved length 10 of the reversely curved bar 7 is offset laterally from the straight line connecting its ends and is also slightly raised above the plane of the threading slot 5. 90 This portion 10 substantially follows that part of the threading slot 5 which lies directly beneath it. The length 10 is connected with the forward end 8 by a relatively short oppositely curved portion 10¹. 100 The rear curved length 11 of the reversely curved bar 7 is disposed in a plane slightly below that of the length 10 and is connected by a downwardly inclined and oppositely curved portion 11¹ with the rear end 9. The portions 10¹ and 11¹ preferably cross the slot 5 at substantially right angles and are disposed in the same general parallel direction. These portions therefore present bars to a direct dethreading line of the threading.

In the threading

is passed above the portion 10¹ of the bar 10 on the far side thereof, considering the delivery end of the eye as the near side of the shuttle and referring to the parts as they are disposed in Fig. 1. The thread is next drawn down across the bar 10 into that part of the slot 5 lying beyond the portion 10¹ of the bar and the intersection of the slots 5 and 6 until it lands at the intersection of said slots. At this moment the thread occupies a path indicated by the dotted lines T¹ in Fig. 1, wherein the thread is represented as drawing across the bar 10 as substantially its point of deflection from the portion 10¹. This is performed by the operative to the usual forward and slightly lateral movement of the hand.

The next usual movement and the one next made with our invention is a rearward pull on the thread. Its effect is as follows: The slight backward movement of the hand causes the thread T¹ while being pulled through the slots 5 and 6, to travel back on the bar 10 across which it is being drawn until it strikes the rear reversely curved and slightly downwardly inclined portion 11 thereof. The thread, sliding down this portion is transferred from the far to the near side of the bar. When it reaches the point of deflection of the parts 11 and 11¹, it is deflected in under the bar and as it travels down this portion 11¹ it is guided into the slot 5 at substantially its point of entrance from the bobbin chamber. The thread is now wholly laid in both slots and during this movement it has been slipping back toward the direct connection between the eye 4 and the bobbin chamber 2 so that as soon as it passed the portion 11¹ it was laid in the eye 4. With the thread thus laid, any unthreading tendency originating in the bobbin chamber is squarely met by the portions 11 and 11¹ which positively bar escape of the thread. Any tendency of the thread to escape by a move back from the opposite end of the slot 5 is squarely met in the part 10¹ which crosses the slot at practically a right angle. The thread is therefore absolutely barred at either end of the slot 5 from voluntary movement.

The eye 4 is provided with a guard substantially conforming to the contour of the eye at its delivery end and having a thread entrance disposed substantially opposite to the plane of entry of the slot 6 into the eye 4. This guard is preferably formed of a single length of wire which is bent between its ends to form a thread tensioning device and in addition is so shaped at its delivery end as to perform its appointed function of preventing escape of the thread back into the slot 6. This guard comprises a relatively straight shank 13 extending transverse and disposed below the threading

passage 6 into the eye 4. The free end of the shank 13 is clenched into the wood of the shuttle to lock the guard in place.

The shank 13 is bent between its ends to develop a reverse curve disposed between the delivery end of the slot 6 into the eye 4 and the entrance end of the threading slot 5 into the bobbin chamber 2. This curve is preferably in the form of a double loop comprising a substantially vertical portion 13¹ extending above the shank 13. The portion 13¹ is bent over upon itself and extends downwardly in the form of an arm 13² to a point below the plane of the shank 13. The portion 13² is bent over upon itself and extends upwardly in the form of an arm 13³ which is spaced from but is disposed in substantial parallelism with the arms 13¹ and 13² and is extended upwardly to a point above the plane of entry of the slot 6 into the eye 4. The development of the shank 13 from this point to the delivery end of the eye 4 is in the form of a relatively straight portion 13⁴ disposed above the shank 13 and substantially parallel thereto. The portion 13⁴ constitutes a thread supporting member disposed slightly above the plane of entry of the slot 6 into the eye 4 and is effective to guide the thread into the loop defined by the arms 13² and 13³. The portion 13⁴ terminates in a loop 14 substantially conforming to the shape of the eye 4. The loop 14 crosses itself below the level of the thread supporting portion 13⁴ but leaves a space between its overlapped portions through which the thread enters from the slot 6. The downwardly deflected arm 14 of the loop is connected at its lower end by a portion 14¹ with the opposite upwardly deflected arm 12 of the loop. This arm 12 extends as an upwardly slanting portion 15 on the side of the threading slot opposite to the direction of its original deflection from the portion 13⁴. The portion 15 crosses the portion 14 below the level of the portion 13⁴ but leaves a space between its overlap sufficiently large to permit entrance of the thread from the slot 6. Near its overlap the portion 15 is deflected upwardly to provide a deflecting portion 15¹ overlying the plane of entry of the threading slot and disposed at an acute angle thereto. The portion 15¹ deflects the thread downwardly onto the thread supporting portion 13⁴ and from thence into the confines of the loop. This portion terminates on the side of the threading slot opposite to the direction of its original deflection from the transverse shank in an inwardly bent pin 16 which is driven into the wood of the shuttle on the upper side of the slot 6 to assist in holding the guard in place.

It will be observed that when the thread

passes out of the slot 6 it is deflected by the portion 15¹ onto the thread supporting portion 13⁴ from which it travels into the loop defined by the arms 13² and 13³ and travels 5 around the portions 13¹ and 13² as guide posts. As the thread descends it moves down the upwardly sloped portion 15 of the loop 14 until it is entered within the loop. Any tendency of the thread to run 10 back into the slot 6 is opposed by the vertical portion 14 of the loop and any tendency of the thread to escape by an upward movement is met by the relatively horizontal portion 15 of the loop. The thread is 15 therefore held against escape by any path other than its true path of delivery and feeds from the eye in a uniform even manner. The development of the guard between the loop 14 and the free end of the 20 shank serves to exert an even uniform tension on the thread during the run of the shuttle as well as preventing its escape.

Various modifications in the form and construction of our device may obviously 25 be resorted to within the limits of the appended claims.

What we therefore claim and desire to secure by Letters Patent is:

1. In combination with a shuttle having 30 a delivery eye and a threading passage leading thereto, a member in said eye having a transversely disposed thread supporting portion adjacent the delivery end of the eye, said member reversely curved between its ends and providing a tensioning 35 device and beyond said curve extending as an arm disposed transversely across the shuttle and across which arm the thread from the bobbin runs.

40 2. In combination with a shuttle having a delivery eye and a threading passage leading thereto, a member in said eye having a relatively short transversely disposed thread supporting portion, said member bent

downwardly and upwardly and downwardly 45 again in spaced vertically disposed turns providing a tensioning device, and said member beyond said tensioning device extending as an arm transversely across the shuttle, and across which arm the thread 50 from the bobbin runs.

3. In combination with a shuttle having a delivery eye and a threading passage leading thereto, a member set in said eye and having a horizontally disposed thread supporting portion bent downwardly at one end at substantially right angles and providing a thread tensioning device, a guide beyond said bend past which the thread runs, said guard member beyond said guide 55 extending as a portion disposed transversely across the shuttle and over which the thread from the bobbin runs.

4. A device for use with a shuttle having a delivery eye, a bobbin chamber, and a 60 threading passage connecting said eye and chamber, consisting of a guard member set in said eye, said member having a transversely disposed thread supporting portion terminating at one end in a loop substantially conforming to the delivery end of 65 said eye and said loop having a portion overlying said threading passage at its point of entry into the eye, said thread supporting portion terminating at its other end in 70 a thread tensioning device, and said guard member beyond said tensioning device extending transversely across the shuttle and providing a bar over which the thread from 75 the bobbin runs.

In testimony whereof we affix our signatures in presence of two witnesses.
